UNITED STATES PATENT OFFICE.

DANIEL L. CHANDLER, OF BOSTON, MASSACHUSETTS, ASSIGNOR, BY MESNE ASSIGNMENTS, TO WILLIAM H. WHITCOMB, OF NEWTON, MASSACHUSETTS.

COIN-CONTROLLED AND CHANGE-MAKING TURNSTILE APPARATUS.

Application filed January 11, 1924. Serial No. 685,581.

This invention relates to a coin-controlled and change-making turnstile apparatus.

The object of the invention is to provide an apparatus which can be installed at the entrance to railway stations, railway cars, or in any place where it is desired to have a fare or admission fee or exit fee paid by the patron.

The apparatus of this invention is particularly adapted to be used in railway stations and on railway cars. In street railway cars it is the custom in some instances for the passenger to pay when entering the car, and the operation of the apparatus in such an instance is hereinafter described as "Operation No. 1".

In other instances the custom is for the passenger to pay when passing out of the car, and the operation of the apparatus in this instance is hereinafter described as "Operation No. 2".

In still other instances the passenger is obliged to pay when entering the car and when passing out of the car, and in such a case the operation of the apparatus is hereinafter described as "Operation No. 3".

The apparatus of this invention may also be set so that the turnstile can be rotated to allow the patron to pass in, or to pass out, without paying anything and the operation of the apparatus to secure this result is hereinafter described as "Operation No. 4".

The apparatus is also capable of ejecting a coin which is not of predetermined diameter and thickness, or any spurious coin, or so-called slug, which is not of predetermined thickness and diameter, and the manner in which this is accomplished by the apparatus of this invention is hereinafter described as "Operation No. 5".

The apparatus of this invention is capable of operation for any of these different conditions, and to these ends the apparatus may be set to operate as follows:—

Operation No. 1.

Assuming that the apparatus is to be used on a railway car, or in a railway station, or at the entrance to a theater, concert hall, or the like, and that it is desired that the patron shall pay before he enters the station or other place set forth, and that he shall pay a certain amount of fare or entrance

fee, the apparatus of this invention is so constructed and can be so set that the patron, as he enters, passes through a passageway, upon one side of which is preferably arranged a rail, and on the opposite side of the passageway the apparatus of this invention is located.

The apparatus embodies therein a rotary member provided with a plurality of radially extending arms constituting a turnstile and when the apparatus is in its normal position, one of these arms extends transversely of the passageway to prevent the patron from passing through unless he first deposits a coin in the apparatus.

The particular embodiment of my invention hereinafter described and claimed is adapted to be used where the fare is ten cents. After the ten cents is deposited in a slot provided in the apparatus and the patron then moves forward, he pushes the arm of the turnstile which extends across the passageway and rotates the rotary member by said arm, through an angle of 90°. This allows him to pass through the passageway, and another arm of the turnstile will extend across the passageway as before. If the patron does not push the arm of the turnstile through the entire 90°, the apparatus operates to continue the movement of the turnstile until the arm has passed through an angle of 90°, if he moves it at least 45°. If the patron, instead of inserting the exact fare, ten cents in this particular instance, should insert a twenty-five cent coin, the operation would be the same as hereinbefore set forth, but in addition thereto, the apparatus would deliver to the patron change of fifteen cents. If the patron inserts fifty cents in the apparatus, then he will be enabled to pass through the passageway and receive in change forty cents.

The apparatus is so constructed that the rotary member can be moved through an angle less than 45° without a coin being inserted in the slot, but in such an instance, the arms of the turnstile of this invention would turn through an angle substantially less than 45° and this would prevent the patron from passing through the passageway. Then, upon releasing the turnstile, the rotary member and the arms of the turn-

stile would be automatically returned to their initial positions. The same would be true, if the patron inserted in the slot a coin, whether spurious or not, which did not 5 measure a predetermined diameter and thickness.

In this particular embodiment of my invention, the diameter and thickness of the coin, or other article inserted in the slot, 10 must be of the diameter and thickness of a ten cent piece, a twenty-five cent piece or a fifty cent piece, in order for the turnstile to be operated to allow the passenger to pass through. Anything, other than an article 15 of such dimensions, would not enable the patron to rotate the turnstile so that he could pass through the passageway, and would be returned by the rotation of the rotary member to an angle less than 45°, as aforesaid, 20 to the patron. Under these circumstances, upon releasing the arm of the turnstile, after the article has been returned to the patron, the rotary member and the arms of the turnstile will be automatically returned to their 25 initial positions.

After having paid his fare and his change having been returned to him, in the manner hereinbefore set forth, and the patron has passed into the car, station, or other place 30 where the apparatus is installed, he can, when the apparatus is set for this particular operation, return through the passageway and rotate the turnstile in the opposite direction without depositing any coin.

35

Operation No. 2.

In operation No. 2 the apparatus is set so that the patron can pass outwardly through the passageway upon depositing a coin in 40 the coin slot of a predetermined thickness and diameter, and can pass inwardly without deposit of any coin.

Operation No. 3.

45 The apparatus is provided with a manually operable mechanism which can be changed so as to set the machine to operate as set forth in "Operation No. 1", that is, can be set so that the turnstile is rendered 50 operable to allow the patron to enter by the deposit of a coin of predetermined thickness and diameter, as in "Operation No. 1", and also the patron would be obliged to insert in the coin slot a coin of predetermined thickness and diameter, in order to be able to rotate the turnstile and pass outwardly through 55 the passageway. In this operation of the apparatus, change is returned to the patron, as hereinbefore described in "Operation No. 60 1" and the turnstile is rendered non-rotatable to an extent sufficient to allow the patron to pass inwardly or outwardly, when a coin, spurious or otherwise, which is not of a predetermined diameter or thickness is inserted 65 in the coin slot, and such coin is returned to

the patron as hereinbefore set forth in "Operation No. 1".

Operation No. 4.

In certain conditions it is desirable that 70 the turnstile should be operable by the patron without inserting a coin either when he is passing out of the car, station, or other place where the apparatus is installed, and the apparatus of this invention may be so set 75 that it may be operated in this manner.

Operation No. 5.

Under any of the conditions hereinbefore set forth in operations Nos. 1, 2 and 3, if the 80 patron deposits in the coin slot of the apparatus, a coin which is not of a predetermined diameter or thickness, or both, then the turnstile cannot be operated to allow the patron to pass through the passageway, but 85 the coin will be ejected from the apparatus and the turnstile will not be unlocked to allow the patron to pass through. This will be true of any article which differs in diameter or thickness from the diameter and 90 thickness of the coin intended to be used in the apparatus. In this particular embodiment of my invention, therefore, any coin which differs in thickness or diameter from a ten cent piece, a twenty-five cent piece or a 95 fifty cent piece, when inserted in the coin slot of the apparatus will not render the apparatus operable to rotate the turnstile and allow the patron to pass through.

The invention consists in a coin controlled 100 and change-making turnstile apparatus embodying mechanism whereby the foregoing operations may be performed and in the combination and arrangement of parts disclosed in the following specification and particularly pointed out in the claims. 105

Referring to the drawings:—

Figure 1 is a plan view of my improved change-making turnstile apparatus, the side rail of the passageway being shown broken 110 away.

Fig. 2 is a front elevation of the same, with the casing which encloses the instrumentalities of the apparatus removed but shown in dotted lines. 115

Fig. 3 is a rear elevation, partly in section, on a larger scale than Fig. 2, illustrating the different instrumentalities of the apparatus and also illustrating the coin tubes from which change is obtained for the change-making operation of the apparatus, certain parts of the apparatus being broken away to save space. 120

Fig. 4 is a front elevation of the instrumentalities of the apparatus, the top plate being shown in section, and other parts broken away to save space in the drawings. 125

Fig. 5 is a sectional plan taken on line 5—5, Fig. 4, illustrating a portion of the rotary member with a cam attached thereto. 130

Fig. 6 is a detail sectional plan taken on line 6—6, Fig. 4, of a portion of the device for determining in which direction the turnstile can be rotated upon the deposit of a 5 coin of predetermined dimensions in the apparatus.

Fig. 7 is a detail sectional plan on line 5—5, Fig. 4, of a portion of the device illustrated in Fig. 6.

10 Fig. 8 is a detail sectional plan on line 8—8, Fig. 4, of a portion of the device illustrated in Fig. 6.

15 Figs. 9, 10 and 11 are detail sectional plans similar to Figs. 6, 7 and 8, but with the parts set in a different position.

Figs. 12, 13 and 14 are sectional plans similar to Figs. 6, 7 and 8 respectively, but with parts set in different positions.

20 Figs. 15, 16 and 17 are sectional plans similar to Figs. 6, 7 and 8 respectively, but with the parts set in different positions.

Fig. 18 is a sectional elevation taken on line 18—18, Fig. 2, looking toward the right in said figure.

25 Figs. 19, 20, 21 and 22 are enlarged sectional elevations in detail of a portion of the coin detector mechanism taken on line 18—18, Figure 1, and illustrating, enlarged, that portion of the coin thickness detector mechanism which is shown in the upper part 30 of Fig. 18 and showing the parts in different positions assumed relatively to each other in the operation of the machine.

Fig. 23 is a sectional plan taken on line 23—23, Fig. 24, illustrating a portion of the coin diameter detector mechanism and a portion of the change-making mechanism.

Fig. 24 is a sectional elevation taken on line 24—24, Figure 23.

40 Fig. 25 is a left hand side elevation, partly in section, of the mechanism illustrated in Figs. 23 and 24.

Fig. 26 is a detail sectional elevation taken on line 26—26, Fig. 25.

45 Fig. 27 is a detail sectional rear elevation of the coin handling mechanism, partly broken away and shown in section.

Fig. 28 is a detail sectional plan taken on line 28—28, Fig. 27.

50 Fig. 29 is a detail sectional plan taken on line 29—29, Fig. 27.

Figs. 30, 31 and 32 are detail sectional elevations of the coin handling mechanism, similar to Fig. 27 and illustrating the parts 55 in different positions relatively to each other.

Fig. 33 is a detail sectional elevation on line 33—33, Fig. 3, illustrating one of the coin tubes and a portion of the mechanism, whereby the coins are fed out of the tubes.

60 Fig. 34 is a detail plan view of one of the coin feed slides.

Fig. 35 is a detail front elevation of the left hand stop rod.

65 Fig. 36 is a detail elevation of the right hand stop rod.

Like numerals refer to like parts throughout the several views of the drawings.

Operation No. 1.

The apparatus of this invention will first 70 be described, when the mechanism is set to operate in the manner hereinbefore set forth in "Operation No. 1", where the patron is allowed to pass through the passageway to enter the car, station, or other place by de- 75 positing a coin of predetermined thickness and diameter, but not otherwise, and is al- lowed to pass outwardly through the pas- sageway without depositing a coin.

In the drawings, Figures 1 and 2, 30 is the coin-controlled and change-making turnstile apparatus. 31 is the side rail and 32 the passageway between the apparatus and the side rail. 33 is a semi-circular table which is positioned horizontally at approximately 80 the same height as the side rail 31 and which is provided with pockets 34 and 35 constituting receptacles for the change which is returned to the patron by the apparatus. 36 is a casing which contains a plurality of 90 tubes for the change which is to be returned to the patron, and this casing is supported upon a top plate 37 which is fastened to the frame 38 of the apparatus. The frame 38 terminates at the lower end thereof in a cy- 95 lindrical portion 39 which fits into a cor- responding opening 40 in the top member 41 of a hollow base 42. The base 42 is pro- vided with annular flanges 43 fast to the lower end thereof and fastened to the sup- port, upon which the apparatus stands, by 100 screws or bolts 44, see Figs. 2 and 18.

The frame 38 has a rotary member 45 mounted on the cylindrical portion 39 of 105 said frame. This rotary member rests upon the upper end of the top member 41 of the base and projects upwardly into a casing 37' shown in dotted lines in Fig. 2 and is prevented from moving upwardly by a shoul- 110 der 47 on the frame 38. The casing 37' is fastened to the top plate 37. The rotary member 45 constitutes the operating mem- 115 ber of the apparatus and has fastened there- to four arms 48, said arms and the rotary member constituting a turnstile. The arms, as seen in Fig. 2, consists of a rectangular portion 49 which is connected by an angle portion 50 to a flange 51 on the lower end 120 of the rotary member 45 and by these arms a rotary motion is imparted to the rotary member.

The rotary member 45 and the arms 48 are kept in a normal position, as illustrated in Figs. 1 and 2, with one of the arms extending across the passageway 32 by a gear 52 which is fastened to the flange 51 and meshes into a pinion 53, Figs. 3 and 5, fas- 125 tened to the lower end of a vertical shaft 54 which is rotatably mounted in the frame 38, and has fastened to its upper end a crank 130

plate 55, having a crank pin 56 thereon. The crank pin 56 is connected by a spring 57 to a hooked end 58 of a bracket 59 which is fastened to the frame of the machine. As 5 the rotary member 45 is rotated, the gear 52 will rotate the pinion 53 and through the shaft 54, the crank plate 55 and the crank pin 56 will be rotated, thus increasing the tension on the spring 57, which will 10 always bring the crank plate 55 and its pin 56 to the position illustrated in Fig. 3, and through the pinion 53 and gear 52, the rotary member and the turnstile as a whole will be thus brought back to normal position, or forward to a similar normal position, with another arm extending across the passageway, according to the angle through 15 which the turnstile is rotated by the patron, as will be hereinafter more fully described. 20 The turnstile is prevented from being rotated through an angle over 45°, except when a coin of predetermined diameter and thickness is deposited in the coin slot, by a series of stops 60 fast to the upper end of 25 a cylindrical cam 61, the cam 61 being fastened to the gear 52 and thus is fastened to the rotary member 45.

When the turnstile is operated by the 30 patron without inserting a coin in a coin slot 62, provided in the upper end of the frame 38, the rotary member 45 will be free to move with the gear 52, and the cam 61, until one of the stops 60 engages a stop slide 63, Fig. 3, which is slidably mounted on the frame 38. 35 When one of the stops 60 thus engages the stop slide 63 no further movement can be imparted to the rotary member by the arms 48 of the turnstile, in the direction of the arrow *a*, Figure 1, or in a clockwise direction, this being the direction in which it is 40 assumed that the passenger is moving through the passage 32 in the present operation of the apparatus.

When the patron releases the turnstile, the 45 rotary member will be carried back to its initial position by the spring 57, crank pin 56, crank plate 55, shaft 54, pinion 53 and gear 52.

Assuming now that the patron inserts 50 in the slot 62, a twenty-five cent piece, the coin will enter the slot and rest upon the upper end of a vertically movable auxiliary slide 64, as illustrated in dotted lines, Fig. 27. The auxiliary slide 64 is slidably mounted in the frame 38 of the machine and its rear face contacts with and slides against a primary slide 65 which also slides vertically in the frame of the machine, and to which a vertical motion is imparted by a primary lever 74, see Figs. 18, 19, 20, 21, 22, 23, 24, 55 27, 28, 30, 31 and 32. Now upon rotation of the turnstile, the rotary member 45, forming a part thereof, will be rotated, together with the gear 52 and cam 61 and this cam has a 60 cam path 67 provided therein, in which is

positioned a cam roll 68 rotatably mounted upon a cam stud 69 fast to a cam slide 70, which is mounted to slide vertically in ways 71 on the frame of the machine. The slide 70 has a slot 72 on the front face thereof and extending transversely thereacross, into which a stud 73 projects, said stud being rigidly fastened to a primary lever 74. The primary lever 74 is mounted to rock upon a pivot 75 in the lower bifurcated end of a 75 support 76. The support 76 is yieldingly mounted upon the frame by means of a shank 77 extending upwardly from the support 76 and slidably mounted in the frame 38, see Fig. 27. The shank 77 extends above 80 the frame and is encircled by a spring 78, the upper end of which bears against a nut 79 on the upper end of the shank 77, and the lower end of which bears against the frame 38, the spring 78 tending to hold the support 76 upwardly when the parts are in their normal positions. The primary lever 74 is provided with a slot 80 in one end thereof, into which projects a stud 81 which is fast to the primary slide 65. 90

Referring now to Fig. 3 it will be seen that the primary slide 65 has a pin 82 projecting therefrom and into a slot 83 provided in one end of a lock lever 84, which is pivoted at 85 to the frame of the machine, and has 95 in its outer end a spring-actuated latch 86 which, when the parts are in the positions illustrated in Fig. 3, engages a bevelled pin 87 which is fastened to the stop slide 63, so that when the cam slide 70 actuates the 100 primary lever 74 to move it downwardly, the primary slide 65 will be moved downwardly; the lock lever 84 will be moved downwardly at its left hand end Fig. 3 and upwardly at 105 its right hand end, and the latch 86 will engage the pin 87 and move the stop slide 63 upwardly out of the path of the stops 60, so that the rotary member can be rotated to complete its quarter turn. As soon as the stop lever 84 has been rocked to a sufficient extent so that the latch 86 will become disengaged from the pin 87, the stop slide 63 will drop into the path of the next stop 60 on the rotary member. The lowermost position of the slide 65 and the uppermost position of the cam slide 70 will be reached when the cam roll 68 arrives at the portion 88 of the cam path 67, Fig. 3. The next movement of the cam slide 70 will be upwardly, thus moving the lever 74, slide 65 and stop lever 84 to the relative positions illustrated in Fig. 3, the spring-actuated latch 86 being moved backwardly while passing the pin 87 by the bevelled outer end thereof. In order that during the operation 110 of the turnstile described, the coin may be fed into the machine and the change of fifteen cents given to the operator, the following described mechanism is operated. 115

The auxiliary slide and the primary slide 120

are both operated and the auxiliary slide 64 is moved downwardly by an auxiliary lever 89 which is located adjacent to the primary lever 74, and in the rear thereof, as viewed in Fig. 27, but in front of said lever as viewed from the front of the machine. The auxiliary lever 89 is pivoted to a stud 90 fast to the frame of the machine and has a slot in the left hand end thereof, Fig. 27, into which a stud 91, which is fastened to the primary lever 74, projects. The opposite end of the auxiliary lever 89 has a stud 92 projecting thereinto which is fastened to the auxiliary slide 64, see Fig. 28.

15 It will thus be seen that the primary lever 74 is operated as hereinbefore described and rocks upon its pivot 75 and will rock the auxiliary lever 89 upon its pivot 90 in the same direction and to substantially the same extent as illustrated in dotted lines, Fig. 27, whereby the right hand end of the primary lever 74 and the auxiliary lever 89 would be carried downwardly from the position shown in full lines, Fig. 27, to the position shown in dotted lines therein, and this will cause not only the primary slide 65 to move downwardly, but will also cause the auxiliary slide 64 to move downwardly.

It will be understood that the twenty-five cent coin during the operation hereinbefore described, was first placed in the coin slot 62, and assumed the position illustrated in Fig. 19, resting on top of the auxiliary slide 64. When in this position the coin is measured both as to diameter and thickness. To measure the thickness of the coin a plurality of detector fingers 93, 94 and 95 are provided. The finger 93, Figs. 19, 23 and 27, is the detector finger for dimes and quarters. The detector finger 94 is for quarters and halves, and the detector finger 95 is for halves. These fingers are all substantially duplicates and are positioned in recesses 93', 94' and 95' in the primary slide 65.

45 When a ten cent piece is positioned in the coin slot 62, the detector finger 93 will contact therewith during the operation of the rotary member. When a twenty-five cent piece is located in the slot 62, the fingers 93 and 94 will contact therewith during the operation of the machine, and when a fifty cent piece is located in the slot 62, all three of the detector fingers will contact therewith during the operation of the machine.

55 In the present instance a twenty-five cent piece having been inserted in the slot 62, two of the fingers 93 and 94 will contact therewith during the operation of the machine. At first when the twenty-five cent piece is inserted in the slot 62, the fingers 93 and 94, both of which are substantial duplicates, will be locked relatively thereto, as illustrated in Fig. 19, that is, the upper end of each of said fingers has a flat projection 93 thereon which projects into a slot 97 in the

primary slide 65, but does not project into the slot 62.

The fingers 93, 94 and 95 are substantial duplicates of each other and operate in substantially the same manner and therefore, 70 the description of the finger 93 will apply equally well to the other fingers 94 and 95. The said fingers 93, 94 and 95 are pivoted upon a pin 98 fast to the primary slide 65. The lower end of each of the fingers has a 75 projection 99 thereon which, when the parts are in the relative positions illustrated in Fig. 19, and both of the slides 62 and 64 are in their uppermost positions, will bear against a plate 102 which is rigidly fastened to and forms a part of the frame of the machine and will be held thereagainst by a spring 100. A plate 101 has the hardened steel plate 102 set therein, and this hardened steel plate has a recess 103 and a recess 104 80 therein extending thereacross, the recess 103 being of greater depth than the recess 104, and thus between the recess 103 and recess 104 there is a shoulder 105 formed.

In addition to the detector fingers 93, 94 and 95 which contact with the face of the coins, as hereinbefore described, and measure the thickness thereof, there is a detector slide 106 which measures the diameter of the coin which is inserted in the coin slot. This slide 95 is illustrated in Figs. 23, 24 and 25. This slide as illustrated in Fig. 24 is drawn back to its extreme backward position. In said figure, the twenty-five cent coin 107 is shown in position. The detector slide 106 has a pin 108 fast thereto which projects into a slot 109 in the upper end of an arm 110 forming a portion of a lever 111. The lever 111 is pivoted at 112 to the primary slide 65. The said lever 111 has two laterally extending 100 arms 113 and 114 at the lower end thereof. One of these arms has a contact pin 115 fast thereto. The other of said arms 113 is rounded at its outer end and projects beneath a stationary pin 116 which is also 105 rounded on its lower end and is fastened to the frame 38 of the machine. The rounded end of the arm 113 projects into a correspondingly shaped recess 117 in the face of a plate 118, which is loosely suspended on a pin 119 fast to the pin 116. A spring 120 encircles the shank of a screw 121, which is fastened to the pin 116 and projects through a hole formed in the plate 118. The shank 110 of the screw 121 and the pin 119 are both of smaller diameter than the holes in the plate 118, through which they project, so that said plate is to a certain extent loosely mounted upon the pin 116 and therefore upon the frame 38 of the machine, and constitutes a 115 detent.

Upon the first part of the downward movement of the primary slide 65, the lever 111 will be rocked upon its pivot 112 by reason of the end of the arm 113 being lodged 120 130

in the recess 117 and a slight downward movement of the slide 65 will therefore cause the lever 111 to be rocked so as to move the arm 110 and the slide 106 in the direction 5 of the arrow *b*, Fig. 24, until the forward end of said slide contacts with the edge of the coin 107 and holds it firmly against the inner wall 122 of the frame 38. When in this position a V-shaped tooth 123, which projects from the rear face of the slide 106, will be in vertical alignment with a V-shaped recess 124 which is provided in a stationary plate 125, fast to the plate 101, which forms in effect a portion of the frame of the machine. 10

When the parts are in this position, the primary slide 65 can move downwardly to the full extent of its downward movement, as hereinbefore described, and as it so moves 20 the projection 99 on the lever 93 will move toward the left, Fig. 19, part way into the recess 103, and upon still further downward movement, will travel along in the recess 104 until the parts arrive as illustrated in 25 Fig. 21, thus allowing the projection 96 on the lever 93 to contact with one face of the twenty-five cent coin.

The same operation is performed by the lever 94 which also contacts with the twenty-five cent coin 107, and thus the levers 93 and 94 will be carried past the recess 103 without being moved by their respective springs, so as to bring the lower ends thereof to the extreme depth of said recess and thus 30 allow them to engage the shoulder 105 on the plate 102. If this should happen, it will be seen that the further downward movement of the primary slide would be stopped. The lever 95 is prevented from having its lower end forced into the recess 103 by reason of its respective projection 96 contacting at this time with the rear face of the detector slide 106, see particularly Figs. 23 35 and 24. The primary slide is, therefore, free to move downwardly and the auxiliary slide 64 will move with it, said slides being actuated, as hereinbefore described, by their respective levers 74 and 89. When the slides 40 64 and 65 are thus being moved downwardly the V-shaped tooth 123 on the detector slide 106 will pass through the V-shaped recess 124 in the stationary plate 125, and after the slides have been moved downwardly to a sufficient extent, that is, to some extent below the relative positions illustrated in Fig. 45 21, the coin 107 will be brought opposite an opening 126 and this will allow the detector fingers 93 and 94 to be forced by their respective springs toward the right, Fig. 21, and push the coin 107 through said opening 126, whence it will move downwardly 50 through the hollow interior 127 of the frame 38 and into a coin receptacle 128, which is located in the base 42.

60 During the downward movement of the

primary slide and auxiliary slide hereinbefore described, as the coin considered is a twenty-five cent coin, the patron must receive back in change fifteen cents and this is accomplished by the mechanism now about 70 to be described.

A laterally extending arm 129 on the detector slide 106 engages a lever 130 which is fastened to a rock shaft 131, pivotally mounted at its opposite ends in the side 75 walls of the casing 36. The rock shaft 131 has a vertically extending lever 132 fast thereto, which, at its upper end, is connected by a pin 133 to a bracket 134 fast to and projecting downwardly from a coin feed 80 slide 135. This coin feed slide passes beneath two tubes 136 and 137. The tube 136 contains a column of dimes. The tube 137 contains a column of nickels. The coin slide 135 has two circular openings 138 and 139 85 extending therethrough, the opening 138 being normally in alignment with the column of dimes, and the opening 139 being normally in alignment with the column of nickels. Beneath the slide 135 and extending beneath the two columns of dimes and nickels is a stationary plate 140. The slide 135 is provided with a slot 141 through 90 which projects a stationary pin 142 fast to the frame of the machine.

A retaining finger 143 is pivoted at 144 to the frame of the machine and is held by a spring 145 normally in the position illustrated in Fig. 33. The object of this retaining finger is to hold back any coin which tends to be fed out of the column of coins in addition to the lowermost coin in said column of coins, that is, it is to prevent two coins from being fed from one column at the same time. This is accomplished by the 100 lower end of the finger 143 engaging the uppermost of the two coins, so that the lowermost coin can be fed out from under the column of coins and from its respective chute 136 or 137 and drops into a chute 146 105 which is fast to a rock shaft 147 pivoted at its opposite ends at the front and rear walls of the casing 36.

The rock shaft 147 has a handle 148 fast thereto, so that the chute may be manually positioned, as illustrated in Fig. 3, and the change which is deposited therein, as hereinbefore described, will roll out of said chute and into a stationary chute 149 and rolling down the chute 149, the change for the 115 patron will be deposited in the pocket 35 from which he may secure it as he passes along the passageway 32.

The change having been delivered, a continued movement of the rotary member, by 120 means of one of the arms 48 in a clockwise direction, will bring the succeeding arm into the position originally occupied by the first arm, or if the patron does not push the turnstile sufficiently to accomplish this re- 125 130

sult the spring 57, crank plate 56, crank plate 55, shaft 54, pinion 53 and gear 52 will accomplish this result.

During the latter part of the 90° movement of the rotary member 45 in a clockwise direction, the auxiliary and primary slides 64 and 65 will be moved upwardly to their primary positions, or to the positions illustrated in Fig. 19 and as these slides move upwardly, the rounded end of the arm 113 of the lever 111 will engage the underside of the pin 116 and the lever 111 will be tipped so as to move the upper end of the arm 110 of the slide 106 in the opposite direction to the arrow *b* and into its primary position, as illustrated in Fig. 24, the detector slide 106 thus having been moved upwardly by the primary slide 65 until the V-shaped tooth 123 on the rear side thereof has passed through the V-shaped recess 124 and above the plate 125. During this upward movement, also, of the primary and auxiliary slides, the detector fingers 93, 94 and 95 will be returned to the respective positions illustrated by the detector finger 93 in Fig. 19 and the machine is then ready for another patron to pass along the passage 32 into the car, or other place, and to repeat the operation hereinbefore described.

Assuming that a patron inserts a fifty cent piece in the slot 62, instead of a twenty-five cent piece, the operation of the parts hereinbefore described for feeding the coin thus deposited into the receptacle 128 and for delivering to the patron the change, which would in that case be forty cents, is in all respects very similar to the operation of the mechanism hereinbefore described in relation to the operation where a twenty-five cent coin has been inserted in the coin slot. In such an instance, however, all three of the detector fingers 93, 94 and 95 will bear against the face of the fifty cent piece during the downward motion of the slides 64 and 65 and all three of said fingers will be prevented, by said fifty cent piece, from having their lower ends 99 project into the full depth of the recess 103, all as hereinbefore set forth in relation to the fingers 93 and 94.

The detector slide will be operated in the same manner as hereinbefore described, except that it will not move so far to the right in Fig. 24 as when a twenty-five cent piece was located in the coin slot and therefore the V-shaped projection 123 on the back of the slide 106 will be brought into alignment with another V-shaped recess 150 in the stationary plate 125. Then the slides are in position to continue their downward movement and the fifty cent coin will be ejected from the coin slot by all three of the fingers 93, 94 and 95 and will pass through the opening 126 and downwardly into the coin receptacle

128, as hereinbefore described in relation to the twenty-five cent coin.

At the same time during this operation, change of forty cents must be delivered to the patron and this is accomplished by the arm 129 on the slide 106 engaging a lever 151 which is fastened to a rock shaft 152, pivotally mounted at its opposite ends in the sides of the casing 36. The rock shaft 152 has a lever 153 fast thereto and extends vertically upward therefrom. The vertical end of the lever 153 is connected by a pin 154 to a bracket 155 fast to a coin slide 156 which is operated by this mechanism, substantially in the same manner as the coin slide 135 was operated to feed change for a twenty-five cent coin. The slide 156 projects beneath three coin tubes 157, 158 and 159 containing respectively columns of twenty-five cent coins, five cent coins and ten cent coins. The slide 156 has three circular orifices therein instead of two, as shown and described in relation to the slide 135. A twenty-five cent coin, a five cent coin and a ten cent coin are therefore fed from their respective tubes into the inclined chute 146 and roll down said chute into the chute 149 and from thence into the receptacle 35, thus returning to the patron the change for fifty cents.

Assuming that the patron inserts a ten cent coin in the coin slot, in this case no change would be returned to him, as ten cents is assumed to be the full amount of the fare charged. The ten cent coin having been placed in the coin slot 62, the detector finger 93 only will contact with the face thereof during the downward movement of the slides 64 and 65 and the detector slide 106 will be brought forward to engage the edge of the ten cent piece and hold it against the wall 122 of the frame, as hereinbefore described in relation to the twenty-five cent piece and fifty cent piece. In this case, the ten cent piece being smaller than the twenty-five cent piece, the slide 106 will be moved over further toward the right, Fig. 24, and will cover the ends of the projecting flat plates 96 on the fingers 94 and 95. The V-shaped projection 123 will be brought further toward the right in this case than in the case of the fifty cent coin and twenty-five cent coin and will be brought into alignment with the V-shaped recess 160 in the plate 125, see Fig. 23. This movement of the detector slide is accomplished through the mechanism hereinbefore described, and especially by means of the lever 111.

The remainder of the operation of carrying the coin downwardly, ejecting the same into the receptacle 128 and returning the parts to their initial positions, is the same as hereinbefore described in relation to the operation of said mechanisms when a twenty-five cent coin or fifty cent coin is being

handled, except that no mechanism for delivering change is operated, in view of the fact that the detector slide 106 moves further toward the right, Figs. 23 and 24, than in the cases heretofore described. Therefore, the projection 129 will be carried toward the right beyond both of the levers 130 and 151, and consequently the coin-changing mechanism will not be operated.

10 The lever 130 and the lever 151 are each operated by the arm 129 on the detector slide 106 to be moved downwardly to operate their respective coin slides to deliver the change. Each of these levers bears at its outer end 15 upon a lever 161 which is pivoted at 162 to a bracket 163 fast to the underside of the top plate 37 and is held in its normal position, as in Fig. 25, by a spring 164. Another lever 165 is pivoted upon a stud 166 fast to the lever 161, so that it can swing horizontally, the lever 161 swinging in a vertical direction. The rear end of the lever 165 is connected by a spring 167 to a hooked arm 168 fast to the rear end of the lever 161. 20 The forward end of the lever 165 is made oval in cross section, as illustrated in Fig. 26, and when the levers are in their normal positions, as illustrated in Fig. 25, this oval end of the lever 165 is located above the bevelled upper end 167' of a rack 168' which is fast to and forms a part of a bracket 169 fastened at its upper end to the plate 37. Now as either one of the levers 130 or 151 is tipped with its pivot to actuate the 25 change-making mechanism, as hereinbefore described, the lever 161 will be tipped upon its pivot 162 so as to move downwardly at the right hand end thereof and this will carry with it the lever 165. The oval end of the lever 165 will thus engage the teeth on the rack 168' until it passes below the lowermost tooth of the rack, and then upon the return movement of the lever 161, the oval outer end of the lever 165 will engage 30 the bevel lower end of the rack and pass upwardly as illustrated by the dotted position of said lever 165 in Fig. 26 on the rear edge of the rack 168.

When arriving adjacent to the upper end 35 of the rack 168', the outer end of the lever 165 will engage the bevelled lower end 170 of a spring-actuated plate 171 which is supported upon a screw 172 fast to the bracket 169 and having a spring 173 bearing thereagainst and encircling the screw 172, so that as the end of the arm 165 passes upwardly into engagement with the bevelled lower end 170 of the plate 171, the said plate will be moved toward the left, Fig. 26, until the outer end of the lever 165 passes above the upper end of the rack 168', whereupon the spring 173 will force the outer end of the lever 165 over into its initial position, as shown in full lines, Fig. 26, and the levers 40 161, 165 are then in their initial positions

as illustrated in Fig. 25. This return upward movement of the levers 161 and 165 will rock the lever 130, or the lever 151, as the case may be, back to their original positions and through the mechanism hereinbefore described for making change, the respective slides and the levers 130 and 151 will be returned to their initial positions to receive a new set of coins, with which to supply change.

70 It will be understood that the levers 161 and 165 and rack 168' insure the extreme downward movement of the lever 130 or 151 to actuate the change-making slides before said levers and slides can be returned to their initial positions by the spring-actuated lever 161.

75 The operation of the apparatus, as the patron passes outwardly along the passageway 32 and in the opposite direction to the arrow *a*, will now be explained.

80 In "Operation No. 1" now under consideration, the patron pays going in, but does not pay going out, in other words, the patron pays when the rotary member is rotated in a clockwise direction and does not pay when the rotary member is rotated anti-clockwise. As no coin is inserted in the coin slot by the patron, provision must be made for something to take the place of the ten cent piece, twenty-five cent piece or fifty cent piece, or else the primary slide 65 will be locked against downward movement by the detector fingers 93, 94 and 95 and by the detector slide 106, in which case the lock lever 84 90 would not be operated to raise the stop slide 63 and therefore, one of the stops 60 on the rotary member would engage the stop slide 63 upon the rotation of the rotary member by one of the arms 48, and the patron could not pass through the passageway and outwardly therefrom. This condition of affairs is taken care of by the mechanism which is now about to be described.

95 Referring to Figures 4, 5, 6, 7, 8, 18, 35 and 36, 174 and 175 are two stop rods which constitute respectively a left stop rod and a right stop rod, that being their respective locations, as viewed from the front of the apparatus. These rods are supported in a bracket 176 fast to the frame of the machine. The stop rod 174 has an arm 177 extending radially therefrom at its upper end. The rod 175 has an arm 178 extending radially therefrom at its upper end. These 100 rods may be moved longitudinally thereof and rotated by means of the arms 177 and 178 respectively and said rods may be locked in position by the arms 177 and 178 projecting into vertical slots 179 and 180 for the rod 174 and 181 and 182 for the rod 175. The vertical slots 179 and 180 are formed in a segmental flange 183 fast to the bracket 176. The slots 181 and 182 are vertical slots 105 formed in a segmental flange 184. These 110

slots open out of the top of the segmental flanges 183 and 184. The stop rod 174 has a notch 185 extending thereacross at the bottom end thereof, and another notch 186 extending thereacross midway between its ends. The stop rod 175 has a notch 187 extending thereacross at its bottom end and another notch 188 extending thereacross midway between its ends.

10 In "Operation No. 1" the rods 174 and 175 are positioned with their respective notches 186 and 188 respectively in the relative positions illustrated in Fig. 7 and the notches 185 and 187 in the relative 15 positions illustrated in Fig. 8. Between the rods 174 and 175 is positioned a lever 189, which rocks on a pivot 190 on the bracket 176, see Figs. 4 and 18. The lever 189 has pivoted thereto at its upper end a lever 191, 20 its pivot 192 being fast to a plate 193 fast to the lever 189 and forming in effect a portion thereof. A spring 194 is interposed between the upper end of the lever 189 and the rear edge of the lever 191. A coin replacement slide 195 is connected by a pivot 196 to the upper end of the lever 191 and projects therefrom through a hole 197 in the frame 38. The hole 197 opens into and extends transversely of the coin slot 62 and in 25 alignment with the flat projection 96 on the dime detector finger 93, so that when the lever 189 is rocked in a direction to move the slide 195 toward the left, Fig. 18, said slide 30 will project into the coin slot 62 and take the place of a dime to prevent the dime detector 35 finger 93 from being rocked from the position illustrated in Fig. 19 to the position illustrated in Fig. 20. On the lower end of the lever 189 a cam block 198 is pivotally mounted on a vertically extending screw 199 and causes said cam block to be pivotally mounted to swing in a horizontal plane on the bottom of the lever 189. The inner rounded 40 end of the cam block 198 is positioned to be engaged by any one of eight different cam 45 projections 200 on four segmental cam rings 201, which are fastened to the upper end of the cam 61.

Referring to Fig. 5, it will be seen that as 50 the rotary member is rotated in a counter-clockwise direction, one of the cam projections 200 will engage the rounded inner end of the cam block 198. At this time the cam block is in the position illustrated in Fig. 5 55 and rests against the stop rod 175, so that the cam block cannot be rocked upon its pivot 199 and as the stop rod 175 cannot move laterally toward the right, Fig. 5, it follows that the cam block 198 will be pushed 60 outwardly and radially with respect to the rotary member. This will rock the lever 189 upon its pivot, moving the lower end of said lever outwardly and the upper end of said lever inwardly, so that referring to Fig. 18, 65 the slide 195 will be moved by the lever 189

and the lever 191 mounted thereon toward the left, Fig. 18, and will project into and across the coin slot 162 in alignment with the flat projection 96 on the upper end of the dime detector finger 93. The slide 195 constitutes a coin replacing means.

At the same time that the detector finger 93 for the dime coin has been prevented from entering the coin slot 62, as just described, the flat plates on the upper ends of the detector fingers 94 and 95 for the twenty-five cent coin and fifty cent coin respectively will be held in the same position as the detector finger 93 shown in Fig. 19 by the slide 106 which will be pushed toward the right, 75 Figs. 23 and 24, by the lever 111 in a manner hereinbefore described, until the forward end of the slide 106 abuts against the slide 195. This will prevent the upper ends of the detector fingers 94 and 95 from entering the coin slot 62 and will prevent the lower ends thereof from entering the recess 103 to the depth thereof. In other words, the slide 65 can be moved downwardly by the rotation of the rotary member, without such downward movement being interfered with by the lower ends of the detector fingers 93, 94 and 95, or any of them engaging the shoulder 105 in the plate 102.

It will be understood that when the forward end of the slide 106 abuts against the slide 195, as just described, the V-shaped projection 123 on the back of said slide, see Fig. 23, will be in alignment with the V-shaped recess 160 and therefore this V-shaped projection and the slide 106 will not prevent the primary slide 65 from moving downwardly. Therefore, the primary slide 65 is free to move downwardly as the rotary member 45 is rotated in an anti-clockwise direction by the patron in passing out of the passageway 62, and since this is the case, the slide 65 will operate the lock lever 84 to raise the stop slide 63 out of the path of the stops 60 and thus the turnstile can be rotated 100 a quarter turn in an anti-clockwise direction without any coin being inserted in the coin slot, and the parts will be returned to their primary positions.

Counter mechanism.

When the turnstile is operated to turn in a clockwise direction by the patron, as he enters the passageway in "Operation No. 1", as has been heretofore described, a coin is 120 deposited by the patron in the coin slot and in order to register each ten cent fare which has been deposited in the apparatus, as hereinbefore described, a counter mechanism 202 of well-known construction is provided and this counter mechanism is operated by an arm 203 thereon which is rocked by a pin 204 on a bracket 205 which is fastened to and forms a part of an arm 206. The arm 206 is fastened to a vertical shaft 207, rotatably 125 130

mounted in the bracket 176. To the lower end of the shaft 207 is fastened an arm 208, see Figs. 4 and 8, and to the free end of the arm 208 is pivoted at 209 a cam block 210, the rounded inner end of which is adapted to be engaged by any one of four cam projections 211, see Figs. 3 and 5. When one of these cam projections 211 engages the inner rounded end of the cam block 210, while moving in a counterclockwise direction, it will be evident by reference to Fig. 8, that the cam block 210 will swing toward the right, being allowed so to do by the notch 187 at the bottom of the stop rod 175 and therefore, the arm 208 will not be moved to operate the counter mechanism through the shaft 207, arm 206, bracket 205, pin 204 and arm 203.

When, however, the rotary member is moved by one of the arms of the turnstile in a clockwise direction during "Operation No. 1", by the patron entering the car or other place, through the passageway 32, one of the cam projections 211 will engage the rounded inner end of the cam block 210, see Fig. 8, and as the stop rod 174 will prevent the cam block 210 from rocking on its pivot 209, it follows that the cam block will be pushed outwardly and radially from the rotary member and this will move the arm 208 outwardly and will rock the vertical shaft 207, thus rocking the arm 206, bracket 205 and arm 203 to operate the counter mechanism to indicate one fare of ten cents.

It will be understood that during the operation hereinbefore described, of the two cam blocks 198 and 210, that each of these cam blocks is held normally in the respective positions illustrated in Figs. 7 and 8, the cam block 198 being held in the position illustrated in Fig. 7 normally by a spring 212, the lower end of which projects into the front end of the cam block, the upper end of which is fastened to the lever 189. The cam block 210 is held in its normal position as illustrated in Fig. 8, by a spring 213, one end of which is attached to the forward end of the cam block and the other end of which is fastened to a bracket 214 on the arm 208.

Operation No. 2.

In this operation the patron pays when going out, but does not pay when passing in. The relative positions of the stop rods 174 and 175 under these conditions are as illustrated in Figs. 9, 10 and 11, that is, the stop rod 175 is in the same position as in Figs. 12, 13 and 14, but the stop rod 174 is set by moving the arm 177 from the slot 179 over into the slot 180 and thus changing the position of the stop rod 174, particularly as illustrated in Figs. 10 and 11.

The chute 146 is tipped by means of the handle 148 to the position illustrated in dotted lines, Fig. 3, so that the change will

be delivered to the chute 149', thence to the pocket 34.

Now it will be necessary for the patron to pay going out, but not when coming in, and the counter will be operated when the patron goes out, but not when he comes in, on account of the fact, as will be seen by reference to Fig. 10, that when the rotary member is moved in a clockwise direction, the cam block 198 cannot be rocked, as hereinbefore described, on its pivot 199. Therefore the lever 189 will be operated to move the slide 195 into the coin slot and take the place of a coin, so that as hereinbefore described, the turnstile can be rotated in a clockwise direction and at the same time it will be noted by reference to Fig. 11 that the cam block 210 can rock upon its pivot into the notch 185 in the stop rod 174, and therefore, the counter will not be operated to count a fare when the patron is passing in.

When the patron passes out, however, the reverse condition of affairs applies. The cam block 198 can be rocked upon its pivot 199 and therefore the lever 189 will not be operated to move the slide 195 to take the place of a coin in the coin slot. Therefore, a coin must be inserted in the coin slot in order to enable the slide 65 to move downwardly and operate the lever 84 and stop 63, as hereinbefore described, to allow the rotary member to be rotated.

Also, by reference to Fig. 11 it will be seen that when the passenger is passing out and the rotary member is being rotated anti-clockwise, the cam block 210 cannot rock upon its pivot 209 because it will be engaged by the stop rod 175. Therefore the arm 208 will be pushed outwardly, and through the mechanism hereinbefore described will be operated to indicate a fare.

Operation No. 3.

In this operation, as hereinbefore set forth, the apparatus is set so that the patron is obliged to pay when coming in and also when going out.

In order to set the machine for this operation the stop rod 174 is left in the position illustrated in Fig. 6, but the stop rod 175 is placed in the position illustrated in Fig. 12 by raising the rod 175 until the arm 178 is drawn out of the slot 181 and then giving the rod a partial rotation to bring the arm 178 into alignment with the slot 182 and then moving the stop rod 175 downwardly until the arm 178 enters the slot 182 and locks the stop rod 175 in position.

The stop rods 174 and 175 are now in the relative positions illustrated in Figs. 12, 13 and 14 and the operation of the mechanism throughout, is the same as in "Operation No. 1", except that the counter, on account of the position of the notches 185 and 187

in the rods 174 and 175, as illustrated in Fig. 14, will operate when the rotary member is rotated in a clockwise direction and also when it is rotated in an anti-clockwise

5 direction, because the cam block 210 cannot rock upon its pivot 209 and therefore, the arm 208 will be operated as hereinbefore described to actuate the counter mechanism, both when the patron is moving inwardly 10 and rotating the rotary member in a clockwise direction, and also when he is moving outwardly and rotating the rotary member in an anti-clockwise direction.

It will be seen by reference to Fig. 13 that 15 the stop rod 174 is positioned the same as in Fig. 7, but that the stop rod 175 is positioned so that when the rotary member is moving in an anti-clockwise direction the cam block 198 will be rocked into the notch 188 in the rod 175 and therefore, the lever 189 will not be rocked to move the slide 195 into the coin slot 62. Therefore, if the patron neglects to place a coin in the slot 20 62, the coin detector finger 93 will be rocked 25 so that the flat projection 96 thereon will project into the coin slot, and the lower end of the coin detector finger 93 will project into the recess 103 and engage the shoulder 105, preventing the primary slide 65 from 30 moving downwardly and thus preventing the lock lever 84 from lifting the stop slide 63 out of the path of the stops 60, so that the turnstile could not be rotated to allow the patron to pass outwardly without inserting 35 the coin.

Operation No. 4.

In this operation the apparatus is set so 40 that the turnstile may be operated clockwise or anti-clockwise without the patron depositing a fare, and this is accomplished by setting the stop rods 174 and 175, as illustrated in Figs. 15, 16 and 17, with the arms 177 and 178 positioned in the slots 180 and 45 181.

By reference to Figure 16, it will be seen 50 that the cam block 198 cannot be rocked upon its pivot in either direction, on account of said cam block engaging the rods 174 and 175 and on account of the notches 186 and 188 being out of alignment with the cam block 198. Therefore, the cam block 198 will be moved outwardly and the lever 189 will be rocked to position the slide 195 with its 55 end projecting into the coin slot, to take the place of a coin, and the slide 65 can, therefore, be moved downwardly to operate the lock lever 84 and stop slide 63 to move the stop slide out of the path of the stops 60.

60 By reference to Fig. 17 it will also be seen that the counter is not operated under these conditions because the cam block 210 can rock in either direction into the notch 185 in the rod 174, or into the notch 187 in the 65 rod 175, therefore no motion will be impart-

ed to the arm 208, nor to the mechanism connected therewith, whereby the counter is operated, therefore no fare would be registered under these conditions.

Operation No. 5.—Coin ejecting mechanism.

In this case the patron inserts a coin in the coin slot, which is not of predetermined diameter and thickness, namely, in this particular embodiment of my invention, a coin 75 other than a ten cent piece, a twenty-five cent piece, or a fifty cent piece, or the patron inserts in the coin slot a spurious coin, or what is known as a slug, which is not of the same diameter and thickness as a ten cent 80 piece, a twenty-five cent piece or a fifty cent piece. In either of which instances the apparatus of this invention operates to eject the coin or slug and also operates to prevent the patron from rotating the turnstile so as to 85 enter, or so as to pass out of the car, station, or in whatever place the apparatus may be installed.

The mechanism whereby this result is attained will now be described.

In each of the operations Nos. 1, 2, 3 and 4, hereinbefore described, the two slides 65 and 64 move together as one piece, that is, the primary lever 74 and the auxiliary lever 89 move together the same distance and thus 90 their respective slides 65 and 64 move together as one piece, but where a coin other than a coin of predetermined dimensions, such as, a dime, twenty-five cent piece or fifty cent piece, is inserted in the coin slot, the 95 two slides first move together as one piece, downwardly and then they move independently of each other and in opposite directions.

Assuming then that a coin which is not 100 of the dimensions aforesaid is placed in the coin slot 62 and that the coin is thinner and of less diameter than a twenty-five cent piece, the rotary member is rotated by one 105 of the arms 48 of the turnstile in a clockwise direction. This will cause the primary slide 65 and the auxiliary slide 64 to move downwardly from the position illustrated in Fig. 27 to the position illustrated in Fig. 30, the movement of the two slides and of the 110 levers 74 and 89 being accomplished by means of the cam slide 70 and cam 61, as hereinbefore described. As the coin in the coin chute is thinner than a twenty-five cent piece, the coin detector fingers 93 and 94 will 115 move from the position illustrated in Fig. 19 to a position approximating that shown in Fig. 20, that is, the lower ends of the detector fingers 93 and 94 will project into the recess 103 and will engage the shoulder 105. This will stop the downward movement of 120 the primary slide 65. Also, since the coin which has been inserted in the coin slot is of less diameter than a twenty-five cent piece and is not of the same diameter as a fifty cent 125 130

piece or a ten cent piece, the detector slide 106 will be moved forwardly or to the right, see Figs. 23 and 24, in which the forward end thereof engages the edge of the coin in the coin slot and moves it up against the wall 122. Now the projection 123 on the rear face 126 will not register with any of the V-shaped recesses 124, 150 and 160 and therefore, the slide 106 can only be carried down by the primary slide 65, until the tooth 123 will abut against the plate 125, so that for two reasons the primary slide cannot move downwardly beyond the distance necessary to cause the tooth 123 to abut against the plate 125, or the lower ends of the detector fingers 93 and 94 to abut against the shoulder 105.

As soon as the downward movement of the primary slide 65 is thus stopped, the parts then being in the relative positions illustrated in Fig. 30, a further downward movement of the cam slide 70 will cause the parts to assume the relative positions illustrated in Fig. 31, that is, the slide 65 being stationary the stud 81 therein will become stationary and will then become the pivot of the primary lever 74 which, upon further downward movement of the cam slide 70, will be caused by the pin 75, which formerly acted as a pivot for the lever 74, to move downwardly rocking upon the pin 81 and through the stud 91, at the opposite end of the primary lever 74, the auxiliary lever 89 will be tipped upon its stationary pivot 90 and the opposite end of the lever 89 will move upwardly, thus moving upwardly also the stud 92 and the auxiliary slide 64 to which it is fastened. During this movement of the levers 74 and 89 the support 76 will be moved downwardly by the pin 75 and the spring 78 will be compressed to allow this movement to take place.

It will be understood that at this time the V-shaped tooth 123 is bearing against the upper face of the plate 125, due to the fact that the slide 106, of which the tooth 123 forms an integral part, is being held downwardly by the downward pressure of the lever 74 upon the pin 81 in said slide 65.

Now in order that the slide 106 may be returned to its normal position, it is necessary that a slight upward movement should be given to the primary slide 65 in order to move the slide 106 and its V-shaped tooth 123 a slight distance away from the upper face of the plate 125 and this is accomplished as follows:

A lever 215, see Figs. 27, 30, 31, and 32, is pivoted at 216 to the primary slide 65. This lever has two arms, a hook-shaped arm 217 and another arm 218, and the arm 218 has a pin 219 fast thereto and projecting laterally therefrom into a bayonet slot 220 provided in the auxiliary slide 64. A stop plate 221 is rigidly fastened to the frame of the ma-

chine and lies in a slot 222 provided in said frame.

Now as the auxiliary slide 64 moves upwardly, as hereinbefore described, from the position illustrated in Fig. 30 to the position illustrated in Fig. 31, the arm 218 will be moved upwardly by the pin 219 in the horizontal portion of the bayonet slot 220 until the hooked end of the lever 215 engages the upper bevelled end of the stop plate 221, the pin 219 travelling along the horizontal portion of the bayonet slot and out into the vertical portion thereof as shown in Fig. 31 and at the same time while moving from the horizontal to the vertical portion of the bayonet slot, the lever 215 will cause the primary slide to be lifted slightly on account of the hooked end of the lever 215 being at that time in engagement with the bevelled upper end of the stationary plate 221. This slight upward movement of the primary slide 65 will release the pressure of the V-shaped tooth 123 on the slide 106 against the upper face of the plate 125 and allow the slide 106 to be moved toward the left, Fig. 24, or back to its initial position.

This movement of the slide 106 back to its initial position is accomplished in this instance by the rocking of the lever 111 toward the left, Fig. 24, and this rocking of the lever 111 is brought about by a projection 223 on the auxiliary slide 64, which at this time, is moving upwardly and engages the contact pin 115 on the lever 111, thus tipping it upon its pivot 112 as before stated and returning the slide 106 to its initial position.

The slight upward movement of the primary slide 65, hereinbefore described, not only moves the slide 106 upwardly to free the projection 123 from pressure on the upper face of the plate 125, but it also moves the detector fingers 93, 94 and 95 upwardly and carries the detector fingers 93 and 94 out of the recess 103 to the position illustrated in Fig. 19, thus leaving the coin slot open for the further upward movement of the auxiliary slide 64.

The upward movement of the auxiliary slide 64 continues until the parts assume the relative positions illustrated in Fig. 32, where the auxiliary slide is shown in its uppermost position and the coin 224 has been ejected by the auxiliary slide from the coin slot.

As soon as the primary slide 65 has been prevented, in the manner aforesaid, from moving downwardly to the full extent of its normal downward movement, the lock lever 84 will not operate to raise the stop slide 63 out of the path of the stops 60, therefore the rotary member 45 cannot be rotated by the arms 48 of the turnstile to a sufficient extent to allow the patron to pass through the passageway and enter the car, station,

or whatever place the apparatus may be installed in.

After the arm 48 has been released, the rotary member and the turnstile arms will 5 be returned to their initial positions by the mechanism hereinbefore described, and the primary and auxiliary levers 74 and 89, and the primary and auxiliary slides 65 and 64 will be returned to their initial positions as 10 illustrated in full lines in Fig. 27.

When a coin is inserted, which is of the proper diameter, but of insufficient thickness, then one or more of the detector fingers 93, 94, and 95, depending upon the diameter 15 of the coin inserted, that is, as to whether it is a ten cent piece, or a twenty-five cent piece, or a fifty cent piece, will rock to a position approximately shown in Fig. 20, and the lower end will then engage the 20 shoulder 105 on the stationary plate 102, and this will prevent the primary slide from being carried downwardly any further and consequently the primary lever 74 and auxiliary lever 89 will operate as herein- 25 before described to cause the auxiliary slide 64 to move upwardly and eject the coin, and the stop slide 63 will not be operated to allow the turnstile to be rotated beyond 45°.

When a coin of the proper thickness, but 30 not of the proper diameter is inserted, then the ejector fingers would not operate as just described, but the detector slide 106 would be moved as hereinbefore described to engage the edge of the coin in the coin slot, 35 and as the coin in the case supposed is not of a predetermined diameter, the V-shaped tooth 123 would not be brought into alignment with any one of the V-shaped recesses 124, 150 or 160, see Fig. 23, and consequently, 40 upon the primary slide being moved downwardly, the V-shaped tooth 123 would abut against the stationary plate 125 and prevent the primary slide from being moved any further downwardly. When this occurs, the 45 auxiliary lever 89 will be operated as hereinbefore described to move the auxiliary slide upwardly and eject the coin, and the stop slide 63 will not be operated to allow the turnstile to be rotated beyond 45°.

When no coin is inserted and the turnstile is turned, and the stop rods 174 and 175 are not set to allow the turnstile to be rotated, as hereinbefore described, in other words, if they are set as illustrated in Fig. 7, and the 50 turnstile is rotated in the direction of the arrow *a*, without inserting a coin in the coin slot, then the coin replacement slide would not operate and the ejector finger 93, see Fig. 23, would project into the coin slot 55 at its upper end, and its lower end would enter the recess in the plate 102 and abut against the shoulder 105, thus preventing the primary slide from being moved any further downwardly, in which case the auxiliary slide would be operated to move up-

wardly, the same as though a coin of diameter or thickness other than a coin of predetermined diameter or thickness had been deposited in the coin slot, and the stop slide 63 would not be operated to allow the turnstile to be rotated beyond 45°. 70

The receptacle 128 can be inserted in the interior of the base 42 through an opening 225 and locked in the base by a plate 226 which closes the opening 225 and is locked 75 in position on the base by a lock 227. The receptacle 128 also has a door 228 thereon which is locked to the receptacle 128 by a lock 229.

In some of the claims the word "receptacle" is used, but it is to be understood that the term is used in a broad sense and does not refer to any particular receptacle such as the receptacle 128, but any receptacle, the 80 walls of which form an integral part of the frame or base, may be considered a receptacle, in the sense in which the word is used 85 in the claims.

I claim:

1. A coin controlled and change-making 90 turnstile apparatus provided with a coin slot and having, in combination, a rotary member, locking means embodying a reciprocatory slide adapted to be engaged by and to prevent said rotary member from being rotated beyond a predetermined angle and manually operable mechanism rendered operable by the depositing of a coin of predetermined dimensions in said coin slot out of engagement with said rotary member and by the rotation of said rotary member to operate said locking means to allow said rotary member to be rotated through an angle greater than said predetermined angle and feed said coin from said coin slot to the 95 interior of said apparatus and mechanism operated by the rotation of said rotary member through said greater angle to eject from the apparatus change equal to the difference 100 between the coin deposited in the coin slot and a coin of predetermined denomination. 105

2. A coin controlled turnstile apparatus provided with a coin slot and having, in combination, a rotary member, locking means to prevent said rotary member from being rotated beyond a predetermined angle and mechanism operated by the partial rotation of said rotary member to eject from said coin slot an article which has been deposited therein of dimensions other than 110 those of a coin of predetermined dimensions. 115

3. A coin controlled turnstile apparatus provided with a coin slot and having, in combination, a rotary member, locking means to prevent said rotary member from being rotated beyond a predetermined angle and mechanism operated by the partial manual rotation of said rotary member to eject from said coin slot an article which has been deposited therein of dimensions 120 125 130

other than those of a coin of predetermined dimensions and means to automatically move said rotary member to its normal position after the partial manual rotation of the same has been discontinued.

4. A coin controlled turnstile apparatus provided with a coin slot and having, in combination, a rotary member, locking means to prevent said rotary member from being rotated beyond a predetermined angle and mechanism operated by the partial rotation of said rotary member to eject from said coin slot a disc-shaped article which has been deposited therein with a diameter other than that of a coin of predetermined diameter.

5. A coin controlled turnstile apparatus provided with a coin slot and having, in combination, a rotary member, locking means to prevent said rotary member from being rotated beyond a predetermined angle and mechanism operated by the partial rotation of said rotary member to eject from said coin slot a disc-shaped article which has been deposited therein of a thickness other than that of a coin of predetermined thickness.

6. A coin controlled turnstile apparatus provided with a coin slot and having, in combination, a rotary member, locking means embodying a reciprocatory slide adapted to be engaged by and to prevent said rotary member from being rotated beyond a predetermined angle and manually operable mechanism rendered operable by the depositing of any one of a plurality of coins of different predetermined dimensions in said coin slot out of engagement with said rotary member and by the rotation of said rotary member to operate said locking means to allow said rotary member to be rotated through an angle greater than said predetermined angle and feed the coin so deposited from said coin slot to a receptacle in said apparatus.

7. A coin controlled turnstile apparatus provided with a coin slot and having, in combination, a rotary member, locking means embodying a reciprocatory slide adapted to be engaged by and to prevent said rotary member from being rotated beyond a predetermined angle and manually operable mechanism rendered operable by the depositing of any one of a plurality of coins of different predetermined dimensions in said coin slot out of engagement with said rotary member and by the rotation of said rotary member to operate said locking means to allow said rotary member to be rotated through an angle greater than said predetermined angle and feed the coin so deposited from said coin slot to the interior of said apparatus, a counter and mechanism operated by the rotation of said rotary member through said greater angle to operate

said counter to register the deposit and retention in said machine of a coin.

8. A coin controlled and change-making turnstile apparatus provided with a coin slot and having, in combination, a rotary member, locking means embodying a reciprocatory slide adapted to be engaged by and to prevent said rotary member from being rotated beyond a predetermined angle and manually operable mechanism rendered operable by the depositing of any one of a plurality of coins of different predetermined dimensions in said coin slot out of engagement with said rotary member and by the rotation of said rotary member to operate said locking means to allow said rotary member to be rotated through an angle greater than said predetermined angle and feed the coin so deposited from said coin slot to the interior of said apparatus and mechanism operated by the rotation of said rotary member through said greater angle to eject from the apparatus change equal to the difference between the coin deposited in the coin slot and the coin of predetermined denomination.

9. A coin controlled turnstile apparatus provided with a coin slot and having, in combination, a rotary member, locking means to prevent said locking member from being rotated beyond a predetermined angle in one direction and mechanism rendered operable by the depositing of a coin of predetermined dimensions in said coin slot and by the rotation of said rotary member in said direction to operate said locking means to allow said rotary member to be rotated through an angle greater than said predetermined angle and feed said coin from said coin slot to a receptacle in said apparatus and mechanism operable by the rotation of said rotary member in the opposite direction to operate said locking means to allow said rotary member to be rotated in said opposite direction through an angle greater than said predetermined angle.

10. A coin controlled turnstile apparatus provided with a coin slot and having, in combination, a rotary member, locking means to prevent said rotary member from being rotated beyond a predetermined angle in a clockwise or in an anti-clockwise direction and mechanism rendered operable by the depositing of a coin of predetermined dimensions in said coin slot and by the rotation of said rotary member in a clockwise direction to operate said locking means to allow said rotary member to be rotated through an angle greater than said predetermined angle and feed said coin from said coin slot to a receptacle in said apparatus, said mechanism being rendered operable by the depositing of another coin of predetermined dimensions in said coin slot and by the rotation of said rotary member in an

anti-clockwise direction to operate said locking means to allow said rotary member to be rotated in an anti-clockwise direction through an angle greater than said predetermined angle and feed said last-named coin from said coin slot to a receptacle in said apparatus.

11. A coin controlled turnstile apparatus provided with a coin slot and having, in combination, a rotary member, locking means to prevent said rotary member from being rotated beyond a predetermined angle in a clockwise or in an anti-clockwise direction and mechanism rendered operable by the depositing of a coin of predetermined dimensions in said coin slot and by the rotation of said rotary member in a clockwise direction to operate said locking means to allow said rotary member to be rotated through an angle greater than said predetermined angle and feed said coin from said coin slot to a receptacle in said apparatus, said mechanism being rendered operable by the depositing of a coin of predetermined dimensions in said coin slot and by the rotation of said rotary member in an anti-clockwise direction to operate said locking means to allow said rotary member to be rotated in an anti-clockwise direction through an angle greater than said predetermined angle and feed said last-named coin from said coin slot to a receptacle in said apparatus and a counter and mechanism operated by the rotation of said rotary member in a clockwise direction through said greater angle to operate said counter to register the deposit and retention in said machine of a coin, said counter mechanism being also operated by the rotation of said rotary member in an anti-clockwise direction through said greater angle to operate said counter to register the deposit and retention in said machine of a coin.

12. A coin controlled and change-making turnstile apparatus provided with a coin slot and having, in combination, a rotary member, locking means to prevent said rotary member from being rotated beyond a predetermined angle in a clockwise or in an anti-clockwise direction and mechanism rendered operable by the depositing of a coin of predetermined dimensions in said coin slot and by the rotation of said rotary member in a clockwise direction to operate said locking mechanism to allow said rotary member to be rotated through an angle greater than said predetermined angle and feed said coin from said coin slot to a receptacle in said apparatus, said mechanism being rendered operable by the depositing of a second coin of predetermined dimensions in said coin slot and by the rotation of said rotary member in an anti-clockwise direction to operate said locking mechanism to allow said rotary member to be rotated

in an anti-clockwise direction through an angle greater than said predetermined angle and feed said last-named coin from said coin slot to the interior of said apparatus and mechanism operated by the rotation of said rotary member in a clockwise direction through said greater angle to eject from the apparatus change equal to the difference between the coin deposited in the coin slot and a coin of predetermined denomination, said last-named mechanism being also operated by the rotation of said rotary member in an anti-clockwise direction through said greater angle to eject from the apparatus change equal to the difference between the second coin deposited in the coin slot and a coin of predetermined denomination.

13. A coin controlled turnstile apparatus provided with a coin slot having, in combination, a rotary member, locking means to prevent said rotary member from being rotated beyond a predetermined angle and a reciprocatory member adapted to be actuated by the partial rotation of said rotary member to operate said locking means to allow said rotary member to be rotated through an angle greater than said predetermined angle, detector means on said reciprocatory member adapted to project into said coin slot and a stop positioned to be engaged by said detector means to prevent the movement of said reciprocatory member for the purpose aforesaid.

14. A coin controlled turnstile apparatus provided with a coin slot having, in combination, a rotary member, locking means to prevent said rotary member from being rotated beyond a predetermined angle and a reciprocatory member adapted to be actuated by the partial rotation of said rotary member to operate said locking means to allow said rotary member to be rotated through an angle greater than said predetermined angle, detector means on said reciprocatory member adapted to project into said coin slot and a stop positioned to be engaged by said detector means to prevent the movement of said reciprocatory member for the purpose aforesaid, said detector means being adapted to be held out of engagement with said stop during the movement of said reciprocatory member by a coin of predetermined thickness positioned in said coin slot.

15. A coin controlled turnstile apparatus provided with a coin slot having, in combination, a rotary member, locking means to prevent said rotary member from being rotated beyond a predetermined angle and a reciprocating member adapted to be actuated by the partial rotation of said rotary member to operate said locking means to allow said rotary member to be rotated through an angle greater than said predetermined angle, detector means on said reciprocating member adapted to project into said coin slot and

a stop positioned to be engaged by said detector means to prevent the movement of said reciprocatory member for the purpose aforesaid and coin replacing means adapted 5 to be operated by the rotation of said rotary member to hold said detector means out of engagement with said stop during the movement of said reciprocatory member whereby said locking means may be actuated as afore- 10 said.

16. A coin controlled turnstile apparatus provided with a coin slot and having, in combination, a rotary member, locking means 15 to prevent said rotary member from being rotated beyond a predetermined angle, and mechanism rendered operable by the depositing of a coin of predetermined dimensions in said coin slot and by the rotation of said rotary member to operate said locking means 20 to allow said rotary member to be rotated through an angle greater than said predetermined angle, said mechanism including a primary slide, an auxiliary slide adjacent thereto and forming the bottom of said coin 25 slot, and spring actuated detecting means mounted upon said primary slide and adapted to project into said coin slot and contact with a coin of predetermined thickness positioned in said coin slot; said mechanism 30 being operable by said rotary member to move said primary and said auxiliary slides downwardly and allow said coin to be ejected from said coin slot by said detecting means and through an opening into a 35 receptacle in said apparatus.

17. A coin controlled turnstile apparatus provided with a coin slot and having, in combination, a rotary member, locking means 40 to prevent said rotary member from being rotated beyond a predetermined angle, and mechanism rendered operable by the depositing of a coin of predetermined dimensions in said coin slot and by the rotation of said rotary member to operate said locking means 45 to allow said rotary member to be rotated through an angle greater than said predetermined angle, said mechanism including a primary slide, an auxiliary slide forming the bottom of said coin slot and a detector finger 50 constituting a lever pivoted to said primary slide and adapted to contact with one face of a coin of predetermined thickness positioned in said slot, said mechanism being operable by said rotary member to lower 55 said slides and means to operate said detector finger to eject said coin from said coin slot through an opening and into a receptacle in said apparatus.

18. A coin controlled turnstile apparatus 60 provided with a coin slot and having, in combination a rotary member, locking means to prevent said rotary member from being rotated beyond a predetermined angle, and mechanism rendered operable by the deposit- 65 ing of a coin of predetermined dimensions

in said coin slot and by the rotation of said rotary member to operate said locking means to allow said rotary member to be rotated through an angle greater than said predetermined angle, said mechanism including a 70 primary slide and an auxiliary slide adjacent to each other, said auxiliary slide forming the bottom of said coin slot, a plurality of detector fingers pivotally mounted upon said primary slide and adapted to contact with a face of a coin positioned in said slot, said mechanism being operable by said rotary member to lower said slides and means to operate said detector fingers to eject a coin from said coin slot through an opening and 75 into a receptacle provided in said apparatus. 80

19. A coin controlled turnstile apparatus provided with a coin slot and having, in combination, a rotary member, locking means to prevent said rotary member from being 85 rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, said mechanism including a primary slide, an auxiliary slide, 90 detecting means mounted on said primary slide and adapted to contact with one face of a coin of less than predetermined thickness positioned in said slot and a stop, said mechanism being operable by said rotary member to move said slide downwardly until 95 said detecting means abuts against said stop, whereupon the downward movement of said primary slide ceases and said mechanism is operable to move said auxiliary slide upwardly and eject said coin from said coin 100 slot.

20. A coin controlled turnstile apparatus provided with a coin slot and having, in combination a rotary member, locking means to prevent said rotary member from being 110 rotated beyond a predetermined angle, and mechanism rendered operable by the depositing of a coin of predetermined dimensions in said coin slot and by the rotation of said rotary member to operate said locking means 115 to allow said rotary member to be rotated through an angle greater than said predetermined angle, said mechanism including a primary slide, an auxiliary slide forming the bottom of said coin slot, a detector finger 120 pivotally mounted on said primary slide and adapted to be moved to contact with one face of a coin positioned in the coin slot, a lever connected at one end thereof to said primary slide, a pivot for said lever, a 125 yieldingly mounted support for said pivot, an auxiliary lever connected at one end thereof to said auxiliary slide, a pivot for said auxiliary lever mounted upon a stationary support, a pin connecting two adj- 130

- cent ends of said levers together and means to rock said primary lever to impart a vertical movement to the primary slide, whereby said auxiliary lever may be rocked to 5 impart a vertical movement to said auxiliary slide.
21. A coin controlled turnstile apparatus provided with a coin slot and having, in combination, a rotary member, locking means 10 to prevent said rotary member from being rotated beyond a predetermined angle, and mechanism rendered operable by the depositing of a coin of predetermined dimensions in said coin slot and by the rotation of said 15 rotary member to operate said locking means to allow said rotary member to be rotated through an angle greater than said predetermined angle, said mechanism including a primary slide, an auxiliary slide forming 20 the bottom of said coin slot, a detector finger pivotally mounted on said primary slide and adapted to contact with one face of a coin positioned in said slot, a lever connected at one end thereof to said primary slide, a pivot 25 for said lever, a yielding support for said pivot, an auxiliary lever connected at one end thereof to said auxiliary slide, a pivot for said auxiliary lever mounted upon a stationary support, a pin connecting two 30 adjacent ends of said levers together and means to rock said primary lever to impart a vertical movement to the primary slide, whereby said auxiliary lever may be rocked to 35 impart a vertical movement to said auxiliary slide in the same direction, and a stop adapted to be engaged by said detector finger during the downward movement of said primary slide whereby the downward movement of said primary slide will cease and 40 the pivotal axis of said primary lever will be transferred to its pivotal connection with said primary slide, said yielding support will be moved downwardly and said auxiliary lever will be rocked by said pin in the 45 opposite direction to that of said primary lever whereby said auxiliary slide will be moved upwardly to eject a coin from said coin slot.
22. A coin controlled turnstile apparatus 50 provided with a coin slot having, in combination, a rotary member, an auxiliary slide forming the bottom of said coin slot, a primary slide adjacent to said auxiliary slide, a detector finger pivoted on said primary slide and adapted to contact with a 55 coin located in said coin slot, mechanism actuated by said rotary member adapted to move said slides downwardly, means to replace a coin in said coin slot and mechanism 60 adapted to move said means into said coin slot and into contact with said detector finger, whereby said primary and auxiliary slides may be moved downwardly without inserting a coin in said coin slot, locking 65 means to prevent said rotary member from being rotated beyond a predetermined angle and mechanism operated by said primary slide and by the rotation of said rotary member to operate said locking mechanism and allow said rotary member to be rotated 70 through an angle greater than said predetermined angle.
23. A coin controlled turnstile apparatus 75 provided with a coin slot and having, in combination, a rotary member, locking means to prevent said rotary member from being rotated beyond a predetermined angle, and mechanism rendered operable by the depositing of a coin of predetermined dimensions 80 in said coin slot and by the rotation of said rotary member to operate said locking means to allow said rotary member to be rotated through an angle greater than said predetermined angle, said mechanism including a primary slide, an auxiliary slide forming 85 the bottom of said coin slot, a detector slide mounted upon said primary slide and adapted to be projected into said coin slot, mechanism to impart a vertical movement to said primary and auxiliary slides and means to move said detector slide transversely of said primary slide and into contact with the edge of a coin in said coin slot, said mechanism being adapted to move said primary and auxiliary slides downwardly and allow said 90 coin to pass through an opening into a receptacle provided in said apparatus.
24. A coin controlled turnstile apparatus 95 provided with a coin slot and having, in combination, a rotary member, locking means to prevent said rotary member from being rotated beyond a predetermined angle, a primary slide, an auxiliary slide forming 100 the bottom of said coin slot, a detector slide mounted upon said primary slide and adapted to project into said coin slot, mechanism to impart a vertical movement to said primary and auxiliary slides, means to move said detector slide transversely of said primary slide and into contact with the edge 105 of a coin in said coin slot, said mechanism being adapted to move said primary and auxiliary slides downwardly and operate said locking means to allow said rotary member to be rotated through an angle greater than said predetermined angle and allow said coin to pass through an opening into a receptacle provided in said apparatus.
25. A coin controlled turnstile apparatus 110 provided with a coin slot and having, in combination, a rotary member, locking means to prevent said rotary member from being rotated beyond a predetermined angle, and mechanism rendered operable by the depositing of a coin of predetermined dimensions 115 in said coin slot and by the rotation of said rotary member to operate said locking means to allow said rotary member to be rotated through an angle greater than said predetermined angle, said mechanism including a 120
- 125
- 130

primary slide, an auxiliary slide forming the bottom of said coin slot, a detector slide mounted upon said primary slide and adapted to be projected into said coin slot, said mechanism being operable to impart a vertical movement to said primary and auxiliary slides, means to move said detector slide transversely of said primary slide and into contact with the edge of a coin of predetermined diameter positioned in said coin slot, a detector slide stop, said mechanism being operable to move said primary and auxiliary slides downwardly while said detector slide is held out of alignment with said detector slide stop by said coin of predetermined diameter and allow said coin to pass through an opening into a receptacle provided in said apparatus.

26. A coin controlled turnstile apparatus provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, said mechanism including a primary slide, an auxiliary slide forming the bottom of said coin slot, a detector slide mounted upon said primary slide and adapted to be projected into said coin slot, said mechanism being operable to impart a vertical movement to said primary and auxiliary slides, means to move said detector slide transversely of said primary slide and into contact with the edge of a coin of a diameter differing from that of a coin of predetermined diameter and a detector slide stop, said mechanism being adapted to move said primary and auxiliary slides downwardly until said detector slide engages said detector slide stop, whereupon further downward movement of said primary slide will be stopped, said mechanism thereupon being adapted to move said auxiliary slide upwardly to eject the coin from the coin slot.

27. A coin controlled turnstile apparatus provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, said mechanism including, a primary slide, an auxiliary slide forming the bottom of said coin slot, a detector slide mounted upon said primary slide and adapted to be projected into said coin

slot and contact with the edge of a coin of a diameter differing from a coin of predetermined diameter positioned therein, a lever pivotally connected to said primary slide at one end thereof, a pivot for said lever, a yieldingly mounted support for said pivot, an auxiliary lever connected to said auxiliary slide at one end thereof, a pivot for said auxiliary lever mounted upon a stationary support, a pin connecting two adjacent ends of said levers together and means to rock said primary lever to impart a vertical movement to the primary slide whereby said auxiliary lever may be rocked to impart a vertical movement to said auxiliary slide in the same direction, a detector slide stop adapted to be engaged by said detector slide during the downward movement of said primary slide when said detector slide is in engagement with the edge of said coin whereby the downward movement of said primary slide will cease and the pivotal axis of said primary lever will be transferred to its pivotal connection with said primary slide, said yielding support will be moved downwardly and said auxiliary lever will be rocked in the opposite direction to that of said primary lever whereby said auxiliary slide will be moved upwardly to eject said coin from said coin slot.

28. A coin controlled turnstile apparatus provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, said mechanism including, a primary slide, an auxiliary slide forming the bottom of said coin slot, a detector slide mounted upon said primary slide and adapted to be projected into said coin slot, said mechanism being operable to impart a vertical movement to said primary and auxiliary slides, a lever pivoted to said primary slide, one arm of said lever being connected to said detector slide, a detent engaged by another arm of said lever whereby said detector slide may be moved transversely of said primary slide upon the downward movement thereof and into contact with the edge of a coin in said coin slot, said mechanism being adapted to move said primary and auxiliary slides downwardly and allow said coin to pass through an opening into a receptacle provided in said apparatus.

29. A coin controlled turnstile apparatus provided with a coin slot and having, in combination, a rotary member, locking means to prevent said rotary member from being

rotated beyond a predetermined angle, and mechanism rendered operable by the depositing of a coin of predetermined dimensions in said coin slot and by the rotation 5 of said rotary member to operate said locking means to allow said rotary member to be rotated through an angle greater than said predetermined angle, said mechanism including a primary slide, an auxiliary slide 10 forming the bottom of said coin slot, a detector slide mounted upon said primary slide and adapted to be projected into said coin slot, said mechanism being operable to impart a vertical movement to said primary 15 and auxiliary slides, a lever pivoted to said primary slide, one arm of said lever being connected to said detector slide, a detent engaged by another arm of said lever whereby said detector slide may be moved trans- 20 versely of said primary slide and into contact with the edge of a coin positioned in said coin slot and of a diameter differing from a coin of predetermined diameter and a detector slide stop, said mechanism being 25 adapted to move said primary and auxiliary slides downwardly and said detector slide into engagement with said stop, whereupon the downward movement of said detector slide and primary slide will cease and said 30 auxiliary slide will be moved upwardly to eject said coin from the coin slot.

30. A coin controlled turnstile apparatus provided with a coin slot and having, in combination, a rotary member, locking means 35 to prevent said rotary member from being rotated beyond a predetermined angle, and mechanism rendered operable by the depositing of a coin of predetermined dimensions in said coin slot and by the rotation of said 40 rotary member to operate said locking means to allow said rotary member to be rotated through an angle greater than said predetermined angle, a rotary cam, a pair of oppositely disposed stops, means to replace a coin in said coin slot and mechanism adapted to move said means into said coin slot and embodying a pivotally mounted latch projecting between said stops and adapted to be engaged by said rotary cam, said stops being 45 so positioned relatively to said latch that when the rotary cam is rotated in a clockwise direction, said last-named mechanism will not be operated through said latch to operate said coin replacing means, and when 50 so positioned relatively to said latch that when the rotary cam is rotated in a clockwise direction, said last-named mechanism will not be operated through said latch to operate said coin replacing means, and when 55 rotated in an anti-clockwise direction, the said last-named mechanism will operate said coin replacing means through said latch.

31. A coin controlled turnstile apparatus provided with a coin slot and having, in 60 combination, a rotary member, locking means to prevent said rotary member from being rotated beyond a predetermined angle, and mechanism rendered operable by the depositing of a coin of predetermined dimensions in said coin slot and by the rotation of 65

said rotary member to operate said locking means to allow said rotary member to be rotated through an angle greater than said predetermined angle, a rotary cam, a pair of oppositely disposed stops, means to replace a coin in said coin slot and mechanism adapted to move said means into said coin slot and embodying a pivotally mounted latch projecting between said stops and adapted to be engaged by said rotary cam, said stops being 70 so positioned relatively to said latch that when the rotary cam is rotated in a clockwise direction, said last-named mechanism will be operated through said latch to operate said coin replacing means and when rotated in an anti-clockwise direction, will not operate said last-named mechanism through said latch to operate said coin replacing means. 75

32. A coin controlled turnstile apparatus 80 provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said 85 rotary member to operate said locking means to allow said rotary member to be rotated through an angle greater than said predetermined angle, a rotary cam, a pair of oppositely disposed stops, means to replace a coin in said coin slot and mechanism adapted to move said means into said coin slot and embodying a pivotally mounted latch projecting between said stops and adapted to be engaged by said rotary cam, said stops being 90 so positioned relatively to said latch that when the rotary cam is rotated in either direction, said last-named mechanism will not be operated through said latch to operate said coin replacing means. 95

33. A coin controlled turnstile apparatus 100 provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said 105 rotary member to operate said locking means to allow said rotary member to be rotated through an angle greater than said predetermined angle, a rotary cam, a pair of oppositely disposed stops, means to replace a coin in said coin slot and mechanism adapted to move said means into said coin slot and embodying a pivotally mounted latch projecting between said stops and adapted to be engaged by said rotary cam, said stops being 110 so positioned relatively to said latch that when the rotary cam is rotated in a clockwise direction, said last-named mechanism will not be operated through said latch to operate said coin replacing means. 115

34. A coin controlled and change-making turnstile apparatus provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, said mechanism including a primary slide, an auxiliary slide forming the bottom of said coin slot, coin detecting means mounted on said primary slide, mechanism adapted to move said coin detecting means into engagement with a coin of predetermined dimensions located in said coin slot, a coin changing mechanism, said first-named mechanism being operable to move said primary and auxiliary slides downwardly, whereby said coin may be fed from said coin slot through an opening to a receptacle in said apparatus and said coin changing means operated by the downward movement of said coin detector slide to eject from the machine change equal to the difference between the coin deposited in the coin slot and another coin of predetermined denomination.
35. A coin controlled and change-making turnstile apparatus provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, said mechanism including a primary slide, an auxiliary slide forming the bottom of said coin slot, a coin detector slide mounted in said primary slide, mechanism adapted to move said coin detector slide into engagement with the edge of a coin of predetermined diameter located in said coin slot, a coin changing mechanism, said first-named mechanism being adapted to move said primary and auxiliary slides downwardly whereby said coin may be fed from said coin slot through an opening to a receptacle in said apparatus and said coin changing mechanism operated by the downward movement of said coin detector slide to eject from the machine change equal to the difference between the coin deposited in the coin slot and another coin of predetermined denomination.
36. A coin controlled and change-making turnstile apparatus provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, said mechanism including a primary slide, an auxiliary slide forming the bottom of said coin slot, a coin detector slide mounted in said primary slide, mechanism adapted to move said coin detector slide into engagement with the edge of a coin of predetermined diameter located in said coin slot, a coin changing mechanism, said first-named mechanism being adapted to move said primary and auxiliary slides downwardly whereby said coin may be fed from said coin slot through an opening to a receptacle in said apparatus and said coin changing mechanism operated by the downward movement of said coin detector slide to eject from the machine change equal to the difference between the coin deposited in the coin slot and another coin of predetermined denomination.
37. A coin controlled and change-making apparatus provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, coin detecting means adapted to engage a coin located in said coin slot, a change making mechanism adapted to be engaged by said coin detecting means when said coin detecting means is in engagement with a coin of predetermined dimensions in said coin slot, said first-named mechanism being adapted to move said coin detecting means to operate said change making mechanism when said detecting means is in engagement with a coin of predetermined dimensions, said first-named mechanism being inoperative to move said coin detecting means to operate said change making mechanism when said coin detecting means is in engagement with a coin of dimensions differing from a coin of predetermined dimensions.
38. A coin controlled and change-making apparatus provided with a coin slot and having, in combination, a rotary member, lock-

- ing means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, coin detecting means adapted to engage a coin located in said coin slot, a change making mechanism adapted to be engaged by said coin detecting means when said coin detecting means is in engagement with a coin of predetermined dimensions in said coin slot, said first-named mechanism being adapted to move said coin detecting means to operate said change making mechanism when said detecting means is in engagement with a coin of predetermined dimensions, said first-named mechanism being inoperative to operate said change making mechanism when said coin detecting means is out of engagement with a coin of predetermined dimensions in said coin slot.
- 25 39. A coin controlled turnstile apparatus provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, a rotary cam, means to replace a coin in said coin slot, and mechanism adapted to move said means into said coin slot and embodying a pivotally mounted latch adapted to be engaged by said rotary cam to operate said last-named mechanism, and a stop manually adjustable to be engaged by said latch to render said latch operable or inoperative for the purpose specified.
- 40 40. A coin controlled turnstile apparatus provided with a coin slot and having, in combination, a rotary member, locking means to prevent said rotary member from being rotated beyond a predetermined angle, and mechanism rendered operable by the depositing of a coin of predetermined dimensions, in said coin slot and by the rotation of said rotary member to operate said locking means to allow said rotary member to be rotated through an angle greater than said predetermined angle, a rotary cam, means to replace a coin in said coin slot, and mechanism adapted to move said means into said coin slot and embodying a pivotally mounted latch adapted to be engaged by said rotary cam to operate said last-named mechanism, a pair of oppositely disposed stops between which said latch projects and manually adjustable to render said latch operable when engaged by said rotary cam, or inoperative when engaged by said rotary cam for the purpose specified.
- 5 65 41. A coin controlled and change-making turnstile apparatus provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, said mechanism including coin detecting means adapted to engage a coin located in said coin slot, mechanism adapted to move said coin detecting means into engagement with a coin of predetermined dimensions located in said coin slot, and a change-feeding mechanism adapted to be engaged by said coin detecting means when said coin detecting means is in engagement with a coin of predetermined dimensions in said coin slot, said first-named mechanism being operable to move said coin detecting means to operate said change-making mechanism.
- 15 70 75 80 85 90 95 100 105 110 115 42. A coin controlled and change-making turnstile apparatus provided with a coin slot and having, in combination, a rotary member, locking means to prevent said rotary member from being rotated beyond a predetermined angle, and mechanism rendered operable by the depositing of a coin of predetermined dimensions in said coin slot and by the rotation of said rotary member to operate said locking means to allow said rotary member to be rotated through an angle greater than said predetermined angle, said mechanism including, a coin detector slide adapted to engage the edge of a coin located in said coin slot, mechanism adapted to move said coin detector slide into engagement with a coin of predetermined dimensions located in said coin slot, and a change-feeding mechanism adapted to be engaged by said detector slide when it is in engagement with a coin of predetermined diameter in said coin slot, said first-named mechanism being operable to move said coin detector slide to operate said change-making mechanism.
- 20 25 30 35 40 45 50 55 60 65 70 75 80 85 90 95 100 105 110 115 In testimony whereof I have hereunto set my hand.

DANIEL L. CHANDLER.
